MULTIBAND RECEIVER

Nelson P. Case, Great Neck, N. Y., assignor to
Hazeltine Corporation, a corporation of Delaware

Application May 4, 1937, Serial No. 140,619

8 Claims. (Cl. 250—20)

This invention relates to multiband modulated-carrier signal receivers and, more particularly, to such receivers operative over a wide range of radio frequencies and including provisions for 5 procuring an approximately uniform amplification at all frequencies of the range.

It has been found difficult to impart such a characteristic to receivers of the type mentioned. For example, the number of amplifying stages 10 which is adequate to procure the desired gain in a band having relatively low mean frequency is frequently insufficient to procure the desired gain in a band having a relatively high mean frequency, because of the lower attainable gain per 15 stage when operating in the latter band. This difficulty is increased as the difference in the mean frequencies of the bands is increased.

If an automatic amplification control bias is applied to a multielectrode tube used as an oscillator-modulator or frequency changer in such a receiver, such control generally affects to a certain degree the frequency generated by the oscillator, with the result that there is a variation in the oscillation frequency as the amplification 20 control bias varies in response to changes in the amplitude of the received signals. While this variation is only a small percentage of the mean oscillation frequency and, therefore, is not very objectionable when the receiver is operating in a 25 relatively low-frequency band, it becomes particularly objectionable when the receiver is operating in a high-frequency band. Furthermore, if the effect of an increased number of amplifying stages subject to automatic amplification control 30 is provided to procure the desired gain in the high-frequency band, as by reflex amplification of an intermediate-frequency signal, the effective range of automatic amplification control for the high-frequency band is considerably greater than 35 for a low-frequency band.

It is an object of the invention to provide a multiband modulated-carrier receiver which has a minimum number of amplifying tubes and which provides a gain in a high-frequency band 40 or bands approximately equal to that procured in the low-frequency band or bands.

It is a further object of the invention to provide a multiband modulated-carrier receiver of the superheterodyne type in which, in a high-frequency band or bands, frequency variation of the local oscillations with variation in automatic 45 amplification control bias is substantially eliminated and in which the range of the automatic amplification control is approximately the same 50 for all bands of the receiver.

In accordance with one embodiment of this invention, a multiband modulated-carrier receiver comprises a carrier-frequency channel followed by a channel operating at a lower carrier frequency, for example, the intermediate frequency 5 of a superheterodyne receiver. There is also provided means for effectively increasing the number of stages, when the receiver is operating in a band having a relatively high mean frequency, either by reflexing the output of one of the stages 10 of lower carrier frequency through one or more of the stages of higher carrier frequency or by providing for a dual amplification in one of the stages of lower carrier frequency. Also, in accordance with this invention, there is provided 15 means whereby the frequency variation of the local oscillations of a superheterodyne receiver of the type described is reduced or prevented when the receiver is operating in a high-frequency band and whereby the range of the amplification control of the receiver is the same for the low-frequency band or bands as for a high-frequency band or bands.

For a better understanding of the invention, together with other and further objects thereof, 25 reference is had to the following description taken in connection with the accompanying drawings, and its scope will be pointed out in the appended claims. Figs. 1 and 2 of the drawings are circuit diagrams, partly schematic, each 30 illustrating an embodiment of the invention as incorporated in a multiband modulated-carrier signal receiver of the superheterodyne type.

Referring now to Fig. 1 of the drawings, there is shown a circuit diagram of a complete modulated-carrier signal receiver of the superheterodyne type embodying the invention, in which certain conventional portions are indicated schematically since, per se, they form no part of the invention. This receiver comprises, in cascade, 35 an antenna circuit 9, a tunable radio-frequency selector 16, a radio-frequency amplifier tube 10, a tunable radio-frequency selector 17, a frequency changer or oscillator-modulator tube 11 provided with an oscillation network 23, an intermediate-frequency selector 57, an intermediate-frequency amplifier 12 of one or more stages, a detector and A. V. C. supply 13, an audio-frequency amplifier 14 of one or more stages, and a loud-speaker 15.

In order to tune radio-frequency selector networks 16 and 17 and the oscillation circuit 23, there are provided tuning condensers 28, 29, and 30, respectively, preferably ganged for unicontrol, as shown in the drawings. The radio-frequency 55

selector 16 comprises a group of primary windings 31, 32, and 33, inductively coupled to a group of secondary windings 34, 35, and 36, respectively, together with switches 19 and 20 for selectively connecting the windings in circuit for operation over the several bands to which the receiver is tunable. Similarly, radio-frequency selector 17 comprises a group of primary windings 38, 39, and 40 inductively coupled to a group of secondary windings 41, 42, and 43, respectively, and selector switches 27 and 22, while the oscillation circuit 23 includes the inductance windings 45, 46, and 47 to which are coupled the feed-back windings 48, 49, and 50, respectively, and the selector switches 24 and 25. Suitable parallel and series-aligning condensers may be provided for the several tunable circuits, as shown, in accordance with conventional practice. The series-aligning condensers of the oscillation network 23 may be common to the oscillator-grid and oscillator-anode circuits of the oscillator-modulator 11, as shown, to provide substantially uniform oscillation voltage, in a conventional manner. Suitable operating potentials are supplied to the input electrodes of tubes 10 and 11 from sources indicated at +B and +Sc. Automatic amplification control bias derived from the unit 13 is supplied to the tube 10, to the tube 11 (in the two lower frequency bands), and to one or more of the tubes in the 30 intermediate-frequency amplifier 12, all in a conventional manner.

The output circuit of the oscillator-modulator 11 is coupled to the intermediate-frequency amplifier 12 through a coupling network 57 comprising a pair of double-tuned intermediate-frequency transformers with windings 54, 58 and 60, 61 coupled by a link circuit including windings 59 and 62, inductively coupled to windings 58 and 60, respectively. The transformers 54, 58 and 60, 61 and their associated windings 59 and 62 are appropriately individually shielded, as indicated.

Neglecting for the moment the operation of the parts of the system involving the present invention, the system described above includes the features of a conventional superheterodyne multi-band receiver. The operation of such a receiver being well understood in the art, detailed explanation thereof is deemed unnecessary. Briefly, however, when operating in the low-frequency or middle-frequency band, a desired modulated-carrier signal intercepted by the antenna 9 is selectively amplified in the radio-frequency selectors 16 and 17 and amplifier 10 and converted in frequency changer 11 to an intermediate-frequency modulated-carrier signal. This signal is selectively amplified by the intermediate-frequency selector 57 and amplifier 12 and translated therefrom to the detector and A. V. C. supply 13, where the audio frequencies of modulation and the 60 automatic amplification control bias are derived. The audio frequencies of modulation are amplified in the audio-frequency amplifier 14 and reproduced by the loud-speaker 15 in a conventional manner.

Coming now to the parts of the system involved in the present invention, a reflex amplification of the output of frequency changer 11 through amplifier tube 10 is provided in the high-frequency band. To accomplish this, a portion of the intermediate-frequency voltage across winding 58 is applied to the input terminals of amplifier 10 through conductor 67 and through the radio-frequency choke coil 68, as shown in the drawings. A blocking condenser 37, connected in circuit by switch 21, prevents flow of intermediate-frequency

currents to ground through the relatively low-impedance path including coil 36, while the choke 68 prevents the by-passing to ground of received high-frequency currents through the lower portion of winding 58.

In considering the operation of the system described above, it will be assumed that, when the unicontrol switches 19, 20, 21, 22, 24, 25, 26, and 27 are in their lowest or middle positions, as shown in the drawings, the receiver is tuned to a low-frequency band or a middle-frequency band, respectively. Under these conditions the intermediate-frequency output of oscillator-modulator 11 is coupled to the input terminals of intermediate-frequency amplifier 12 through the transformer 54, 58, the link circuit including windings 59 and 62, and transformer 60, 61, and the operation of the system is conventional, as described above. In the high-frequency band, corresponding to the setting of the switches as shown in the drawings, the link circuit is opened at switch 26, removing the coupling between transformers 54, 58 and 60, 61. Under these conditions a portion of the intermediate-frequency output of oscillator-modulator 11 is coupled through transformer 54, 58 to the input terminals of radio-frequency amplifier 10, wherein it is subjected to a reflex amplification. The output circuit of amplifier 10 in the high-frequency band also includes the primary winding 60 of the intermediate-frequency transformer 60, 61, so that the reflexed intermediate-frequency output of amplifier 10 is applied through transformer 60, 61 to the input terminals of intermediate-frequency amplifier 12, from which it is translated through the rest of the receiver in the normal manner.

While the amplification control bias is applied to both of tubes 10 and 11 when operating in the low- and middle-frequency bands, it is not applied to oscillator-modulator 11 in the high-frequency band, thus avoiding the frequency variation of the local oscillations with varying amplification control bias which, as noted above, is particularly serious in the high-frequency bands. At the same time, a full equivalent range of control is procured in the high-frequency band, since the amplification of the signal is effectively subject to a double control in amplifier 10 through which the signal passes twice.

In Fig. 2 of the drawings there is shown another embodiment of the invention applied, as in Fig. 1, to a receiver of the superheterodyne type. Similar elements in the two figures are identified by the same reference numerals. The receiver of Fig. 2 comprises, in cascade, the antenna circuit 9, tunable radio-frequency selectors 16 and 70, a frequency changer or oscillator-modulator 11, provided with an oscillation network 23, an intermediate-frequency transformer 71, an intermediate-frequency amplifier tube 72, 60 an intermediate-frequency transformer 73, a detector and A. V. C. supply 13, an audio-frequency amplifier 14 of one or more stages, and a loud-speaker 15. For operation over the several bands of the receiver of Fig. 2, switches 19, 20, 24, 25, 65 75, and 76 are provided, preferably ganged for unicontrol. Selector 16 is coupled to the input circuit of oscillator-modulator 11 through switch 75, selector circuit 70 comprising windings 77 and 78 for the low- and middle-frequency bands, respectively, and switch 76. Automatic amplification control bias derived from unit 13 is supplied to the tube 11, only in the two lower frequency bands and to the tube 72 in all bands of receiver operation. The intermediate-frequency output 75

of amplifier 72 is coupled to the detector and A. V. C. supply unit 13 through transformer 73, comprising windings 79, 80 with their associated tuning condensers, in all bands of receiver operation.

Again neglecting for the present the operation of the parts of the system involving the present invention, the system described above includes the features of a conventional superheterodyne multiband receiver. When operating in either of the two lower frequency bands, a desired modulated-carrier signal intercepted by antenna 9 is selectively amplified in selectors 16 and 70 and converted in frequency changer 11 to an intermediate-frequency modulated-carrier signal. The intermediate-frequency signal is selectively amplified by the transformer 71, amplifier 72, and transformer 73 and translated therefrom to detector and A. V. C. supply 13, where the audio frequencies of modulation and the automatic amplification control bias voltage are derived. Beyond this point, the operation is identical with that described in connection with Fig. 1.

Coming now to the parts of the system in Fig. 2 involved in the present invention, a dual amplification is effected in amplifier tube 72 in the high-frequency band. In accomplishing this, the carrier-frequency signals selected by selector 16 in the high-frequency band are applied to the grid of tube 72 through the condenser 37. A loss of these signals to ground through the tuned circuit comprising the secondary of intermediate-frequency transformer 71 is prevented by the radio-frequency choke coil 68. The amplified carrier-frequency output of amplifier tube 72 is then applied to the input terminals of frequency changer 11 through the radio-frequency transformer 83, 82, the secondary winding 82 being tuned by tuning condenser 29. The intermediate-frequency output of the frequency changer 11 is selectively translated through the intermediate-frequency transformer 71 and applied to the input terminals of amplifier 72 through the radio-frequency choke 68. The condenser 37 is of relatively low capacitance and serves to prevent the intermediate-frequency currents from draining off to ground through the relatively low-impedance path including winding 36.

As in the system described in Fig. 1, the A. V. C. bias is not applied to the oscillator-modulator 11 in the high-frequency band. Full equivalent automatic amplification control is procured in the high-frequency band of Fig. 2, since the signal is effectively subjected to a double amplification in the controlled amplifier tube 72, through which the signal passes twice.

While there have been described what are at present considered to be the preferred embodiments of the invention, it will be apparent to those skilled in the art that various changes and modifications may be made without departing from the invention, and it is, therefore, aimed in the appended claims to cover all such changes and modifications as fall within the spirit and scope of the invention.

What is claimed is:

1. A multiband modulated-carrier signal receiver having a plurality of stages and tunable over a high-frequency band and one or more low-frequency bands comprising, a first modulated-carrier-frequency channel, a frequency changer coupled to said channel for changing the carrier derived from said channel to a carrier having a different frequency, said frequency be-

ing of a different order of magnitude than that of said first channel in said high-frequency band, a second carrier-frequency channel tuned to the frequency of said second carrier coupled to said frequency changer, an amplifier in one of said channels, an automatic amplification control means connected to a plurality of said receiver stages including said frequency changer and said amplifier, and means for selectively including said amplifier in both of said channels and for simultaneously reducing the effect of said automatic amplification control on said frequency changer for operation in said high-frequency band.

2. A multiband modulated-carrier signal receiver tunable over a high-frequency band and one or more low-frequency bands comprising, a multiband carrier-frequency selector system, an amplifier in said system, a frequency changer coupled to said amplifier, a signal-translating stage, first and second intermediate-frequency transformers, a link circuit coupling said transformers, and means for selectively coupling the output of said frequency changer to said translating stage, either through said first transformer, said link circuit and said second transformer and for simultaneously conditioning said selector system for operation in said low-frequency band or bands, or through said first transformer, said amplifier and said second transformer and for simultaneously conditioning said selector system for operation in said high-frequency band.

3. A multiband superheterodyne signal receiver tunable over a high-frequency band and one or more low-frequency bands comprising, a multiband carrier-frequency selector system, an amplifier in said system, a frequency changer coupled to said amplifier, a signal-translating stage, first and second carrier-frequency selectors, means coupling said selectors, a plurality of switch means for selectively conditioning said receiver for operation in any of said bands, switch means for selectively coupling the output of said frequency changer to said translating stage, either through said first selector, said coupling means and said second selector for operation in said low-frequency band or bands, or through said first selector, said amplifier and said second selector for reflex amplification of the intermediate frequency in said high-frequency band, and unicontrol means for operating said switch means.

4. A multiband modulated-carrier signal receiver comprising a plurality of stages and tunable over a high-frequency band and one or more low-frequency bands comprising, a multiband carrier-frequency selector system, an amplifier in said system, a frequency changer coupled to said amplifier, a signal-translating stage, automatic amplification control means coupled to a plurality of said stages, means for selectively coupling the output of said frequency changer to said signal-translating stage, either directly and for simultaneously conditioning said selector system for operation in said low-frequency band or bands, or through said amplifier and for simultaneously conditioning said selector system for operation in said high-frequency band, and means effective in said high-frequency band to reduce the effect of said automatic amplification control means on one of the receiver stages without substantially reducing the range of amplification control.

5. A multiband modulated-carrier signal receiver comprising a plurality of stages and tunable over a high-frequency band and one or more low-frequency bands comprising, a multi-

band carrier-frequency selector system, an amplifier in said system, a frequency changer coupled to said amplifier, a signal-translating stage, automatic amplification control means coupled to a plurality of said stages, a plurality of switch means for selectively conditioning said receiver for operation in any of said bands, switch means for selectively coupling the output of said frequency changer to said translating stage, either directly for operation in said low-frequency band or bands, or through said amplifier for reflex amplification in said high-frequency band, switch means to reduce the effect of said automatic amplification control means on one of the receiver stages without substantially reducing the range of amplification control, and unicontrol means for operating all of said switch means.

6. A multiband modulated-carrier signal receiver having a plurality of stages and tunable over a high-frequency band and one or more low-frequency bands comprising, a multiband carrier-frequency selector system, an amplifier in said system, a frequency changer coupled to said amplifier, a signal-translating stage, automatic amplification control means coupled to a plurality of the receiver stages including said frequency changer, means for selectively coupling the output of said frequency changer to said signal-translating stage, either directly and for simultaneously conditioning said selector system for operation on said low-frequency band or bands, or through said amplifier and for simultaneously conditioning said selector system for operation in said high-frequency band, and means effective in said high-frequency band to reduce the effect of said automatic amplification control on said frequency changer without substantially reducing the range of automatic amplification control of the receiver.

7. A multiband modulated-carrier signal receiver having a plurality of stages and tunable over a high-frequency band and one or more low-frequency bands comprising, a multiband carrier

frequency selector system, an amplifier in said system, a frequency changer coupled to said amplifier, a signal-translating stage, a plurality of switch means for selectively conditioning said receiver for operation in any of said bands, automatic amplification control means coupled to a plurality of the receiver stages including said frequency changer, switch means for selectively coupling the output of said frequency changer to said signal-translating stage, either directly and for simultaneously conditioning said selector system for operation in said low-frequency band or bands, or through said amplifier and for simultaneously conditioning said selector system for operation in said high-frequency band, switch means effective in said high-frequency band to reduce the effect of said automatic amplification control on said frequency changer and increase the effect thereof on one of the other receiver stages, thereby to procure substantially the same range of automatic amplification control in all bands, and unicontrol means for operating all of said switch means.

8. A multiband modulated-carrier signal receiver having a plurality of stages and tunable over a high-frequency band and one or more low-frequency bands comprising, a multiband carrier-frequency selector system, a frequency changer comprising output terminals, a signal-translating channel coupled to said output terminals, an amplifier in said signal-translating channel, automatic amplification control means coupled to a plurality of the receiver stages including said frequency changer and said amplifier, means for selectively including said amplifier in both of said channels and for simultaneously conditioning said selector system for operation in said high-frequency band, and means effective to reduce the effect of said amplification control on said frequency changer when operating in said high-frequency band.
